CLAIM

The ornamental design for a cartridge for linear surgical stapler, as shown and described.

DESCRIPTION

FIG. 1 is a perspective view of a cartridge for linear surgical stapler, showing our new design;

FIG. 2 is a front elevational view of the cartridge of FIG. 1; FIG. 3 is a rear elevational view of the cartridge of FIG. 1; FIG. 4 is a right elevational view of the cartridge of FIG. 1; FIG. 5 is a left elevational view of the cartridge of FIG. 1; FIG. 6 is a top plan view of the cartridge of FIG. 1; and, FIG. 7 is a bottom plan view of the cartridge of FIG. 1. The cartridge features shown in broken lines are unclaimed environment, and form no part of the claimed design.

1 Claim, 4 Drawing Sheets
